CLAIM

The ornamental design for an earbud case accessory as shown and described.

DESCRIPTION

FIG. 1 is a perspective view of an earbud case accessory, showing our new design;

FIG. 2 is a front view of the earbud case accessory of FIG. 1;

FIG. 3 is a rear view the earbud case accessory of FIG. 1; FIG. 4 is a left side perspective view the earbud case accessory of FIG. 1; and

FIG. 5 is a right side view the earbud case accessory of FIG. 1.

FIG. 6 is a top view of the earbud case accessory of FIG. 1; and,

FIG. 7 is a bottom view of the earbud case accessory of FIG. 1.

The broken lines are for illustrating portions of the earbud case accessory which form no part of the claimed design. The shade lines in the Figures show contour and do not claim surface ornamentation or treatment.

1 Claim, 7 Drawing Sheets
